OF HOPEDALE, MASSACHUSETTS, A CORPORATION OF MAINE.

FEELER MECHANISM FOR LOOMS.

1,387,321.

Specification of Letters Patent.

Patented Aug. 9, 1921.

Application filed October 7, 1919. Serial No. 328,977.

To all whom it may concern:

Be it known that I, ISAAC SNOW, a citizen of the United States, and resident of Lawrence, in the county of Essex and State of Massachusetts, have invented an Improvement in Feeler Mechanism for Looms, of which the following description, in connection with the accompanying drawings, is a specification, like characters on the drawings 10 representing like parts.

This invention relates to feeler mechanisms for looms whereby filling replenishment is effected prior to complete exhaustion of filling in the running shuttle.

15 In that class of feeler mechanisms now generally known as the "side swipe" type, the feeler which detects the condition of filling in the shuttle is given a movement longitudinally of the shuttle when the filling is 20 substantially exhausted, and through a train of mechanism, such movement of the feeler is utilized in effecting replenishment of filling. The lateral or side swipe movement of the feeler has usually been imparted either 25 by the frontward pressure upon the feeler when the filling is substantially exhausted, or by a separate instrumentality, such as a spring which acts to effect such movement at the critical stage of the filling.

30 The present invention has more particular reference to that type of side swipe feeler mechanisms wherein the lateral or side swipe movement of the feeler is due in part at least, to the frontward pressure upon the 35 feeler; and one of the objects of the present invention is to provide a feeler mechanism of this general character, wherein the feeler is given its movement longitudinally of the shuttle, or side swipe movement, by cam 40 mechanism, as will more fully appear.

An important feature of the present invention consists in providing a feeler and a companion or guide member with connections such that the two will be caused to 45 move frontwardly in unison when a working supply of filling is present on a detecting beat, but when the filling is substantially exhausted, the feeler will be given a movement longitudinally of the shuttle by the 50 cam mechanism due to the frontward pressure upon the feeler.

The above and other novel features and combination of parts will be hereinafter described in connection with one good practical form of the invention, and the true scope

of the invention will be described in the claims.

In the drawings:

Figure 1 is a perspective view of the detecting side of the loom, showing more particularly the feeler mechanism and its associated parts; 60

Fig. 2 is an enlarged detail plan view showing the action of the feeler mechanism when the filling is substantially exhausted 65 on a detecting beat; and

Fig. 3 is an enlarged detail showing a portion of the train of mechanism actuated by the feeler to effect replenishment of filling.

The replenishing mechanism and the detail connections therewith for effecting replenishment of filling when the feeler has moved in a direction longitudinally of the shuttle, is not herein shown, as the particulars thereof do not form an intimate part 75 of the present invention, and may be of usual well known construction. 70

A loom frame 1 has mounted thereon the brackets 2, one at either side of the loom, in which is mounted the transverse or rock 80 shaft 3 from which rises the arm 4 having pivoted thereto at 5 the latch 6, the rear end 7 of which is adapted at times to be moved into the path of an actuator 8, which may be either the cam follower or a part connected thereto.

The lay 9 is provided with the usual shuttle-box 10, and its front wall is slotted as at 11 to register with the slot 12 in the wall of the shuttle 13, when the latter is in 90 the detecting box. The shuttle 13 carries the usual filling carrier or bobbin 14.

The shipper stand 15 has extended therefrom the arm 16 upon which is adjustably mounted the bracket 17 by means of a suitable bolt 18 which passes through the slot 19 of the arm 16. 95

The present invention contemplates that the feeler member and its companion or guide member shall be mounted for movement toward and from the front of the loom, and in the present instance, the bracket 17 has secured thereto a feeler stand 20. The feeler stand 20 may be connected to the bracket 17 by screws 21 or other suitable 100 means. Mounted for movement toward and from the front of the loom on the feeler stand 20 is the member 22 which, for identification, will hereinafter be designated the feeler guide. The feeler guide 22 passes 105 110

through an opening in the upstanding rear lug 23 connected to the feeler stand, and its frontwardly extending stem 24 passes through an opening in the front flange 25 of the feeler stand. A spring 26, one end of which bears against the flange 25 and the other against a shoulder 27 formed on or secured to the feeler guide, normally acts to hold the feeler guide 22 in rearward position 10 with the stop pin 28 bearing against the rear flange 23 to limit the rearward movement of the feeler guide.

The feeler 29 is mounted on the feeler stand 20 and passes through an opening or slot 30 formed between the rear flange 23 and the upper surface of the feeler stand, the construction being such that the feeler 29 may be moved frontwardly and have a lateral or side swipe movement. The feeler 29 has a toothed engaging end portion 31 which is adapted to engage a surface within the shuttle on each detecting beat.

In the present instance of the invention, the feeler guide 22 is provided with an inclined or cam surface 32 which is engaged by a cam projection 33 formed upon the feeler 29, the construction being such that when the feeler member 29 receives upon it the frontward push of a working supply of filling in the shuttle, and is consequently prevented from being displaced laterally by the frontward pressure upon it, the inclines or cam connections between the feeler guide and feeler 29, cause the feeler and feeler guide to be moved frontwardly together against the tension of the spring 26. When, however, the filling has become substantially exhausted on a detecting beat, and the feeler 29 is permitted to move in a direction longitudinally of the shuttle by the frontward push upon it, the incline or cam 33 of the feeler member moves frontwardly relative to the incline 32 of the feeler guide, thereby causing the feeler to be moved in a direction longitudinally of the shuttle by the frontward push upon it.

The feeler guide 22 is preferably slotted as at 34, and through the slotted end extends the rear portion of the feeler 29 which is provided with a stop 35 to limit the lateral or side swipe movement of the feeler when the filling is substantially exhausted on a detecting beat. The portion of the feeler 29 within the slot 34 is preferably inclined as at 34^a to form a cam face coöperating with the bottom of the slot, and this incline 34^a operates similarly to the incline 32 to impart lateral movement to the feeler. The feeler 29 is also provided with a stop pin 36 which serves to limit the rearward position of the feeler by engagement with the upstanding flange 23.

The present invention contemplates utilizing the lateral or side swipe movement of the feeler 29 to effect replenishment of fill-

ing, and one good practical form of means to this end consists of a lever 37 pivotally mounted at 38 to the feeler stand, and having an end portion 39 adapted to bear against the feeler. In the present instance of the invention, the rear end portion 39 of the lever 37 has a part embracing the upper and lower surfaces of the feeler, one of said parts consisting of a finger 40 bearing upon the upper surface of the feeler, and the other a finger 41 bearing upon the lower surface of the feeler member, the part 42 between the fingers 40, 41 constituting a bearing surface which rests upon the feeler 29. A spring 43 has one end secured to the feeler stand as at 44, and the other end secured to the rear end portion of the lever 37 as at 45, the construction being such that the spring 43 normally holds the lever 37 yieldingly against the feeler member, and the inclines 32, 33 in their normal position of engagement as indicated in Fig. 3.

The lever 37 has connected thereto one end of a transmitter 46, the other end of which is connected at 47 to one arm of a lever 48 pivoted at 49 to a stand 50 rising from the loom frame. The lever 48 has a finger 51 which underlies the latch 6, the construction being such that when the lever 47 is moved upon its pivotal mounting by the lateral or side swipe movement of the feeler on a detecting beat, the lever 48 will be turned to place the end 7 of the latch 6 in the path of movement of the operating member 8, which upon frontward movement effects replenishment of filling.

When the working supply of filling is present on a detecting beat, the filling engages the toothed or rear engaging end portion 31 of the feeler, and the teeth sink into the mass of filling, so that on the further frontward movement of the filling mass, the feeler 29 is moved frontwardly without permissive movement in a direction longitudinally of the shuttle. The effect of this is that the inclines 32 and 33 remain in their undisturbed relation as indicated in Fig. 3, and the frontward push upon the feeler effects simultaneous movement of the feeler member and feeler guide frontwardly in opposition to the spring 26. When, however, the filling has become substantially exhausted on a detecting beat, the rear end of the feeler is no longer held from movement longitudinally of the shuttle, and as the lay beats 120 up, the frontward push against the feeler 29 causes the feeler to be moved frontwardly relative to the feeler guide 22, and the cam portions 33 and 32 will be relatively moved to thereby effect movement of the feeler in a direction longitudinally of the shuttle until the stop 35 of the feeler engages the side of the guide as indicated in Fig. 2, whereupon, both the feeler and feeler guide are moved frontwardly, the parts assuming the posi-

tion as indicated in Fig. 2. The movement of the feeler in a direction longitudinally of the shuttle which is caused by the relative movement of the inclines 33 and 32, acts 5 upon the rear end portion of a lever 37 to move it upon its pivotal mounting 38 from the position indicated in Fig. 1 to that indicated in Fig. 2, and against the tension of the spring 43. The result is that the lever 10 48 will be turned to lift the end 7 of the latch 6 into the path of movement of the operating member 8. It will thus be noted that when the filling in the shuttle is substantially exhausted on a detecting beat, a 15 frontward movement of the feeler relative to the feeler guide 22, is caused by the frontward push upon the feeler, and the inclines or connection between the feeler and feeler guide, act to positively move the feeler in a 20 direction longitudinally of the shuttle against the tension of the spring 43, but when a working supply of filling is present in the shuttle, and the feeler has no movement longitudinally of the shuttle, then the 25 inclines or connections 33, 32 between the feeler and feeler guide maintain their relative position as the lay beats up and the feeler guide and feeler are moved frontwardly in unison without disturbing the 30 position of the lever 37.

The details of connection between the feeler and feeler guide whereby relative frontward movement of the two will cause lateral or side swipe movement of the feeler 35 may be variously contrived, but the incline or cam portions 32, 33 provide a convenient form of means for such connection.

What is claimed is:—

1. In a feeler mechanism for looms, a 40 feeler guide mounted for movement toward and from the front of the loom, a feeler lying alongside the feeler guide, and mounted for movement toward and from the front of the loom and in a direction longitudinally of 45 the shuttle but held from such longitudinal movement by engagement with the filling on a detecting beat until substantial exhaustion thereof, a coöperating cam and recess, one on the feeler and the other on the feeler 50 guide for causing frontward movement of the feeler to move the guide frontwardly without relative frontward movement of the two when a working supply of filling is present on a detecting beat and for causing 55 the feeler to move laterally away from the feeler guide when filling is substantially exhausted, a stop for limiting the movement of the feeler away from the feeler guide and yielding means tending to hold the cam and 60 recess in engagement.

2. In a feeler mechanism for looms, the combination of a feeler guide yieldingly held in rearward position, a feeler extending alongside the feeler guide, a plurality of engaged inclines on the feeler guide and feeler 65

for moving the latter away from the former and in a direction longitudinally of the shuttle by the forward push upon the feeler on a detecting beat and held from effecting such movement by engagement of 70 the feeler with the filling until substantial exhaustion thereof, means extending between the feeler and feeler guide to limit the movement of the feeler away from the feeler guide and means for replenishing filling 75 when the feeler is moved longitudinally of the shuttle.

3. In a feeler mechanism for looms, the combination of a feeler guide, a spring acting rearwardly upon said guide, a feeler extending alongside the feeler guide, inclines 80 on the feeler guide and feeler at spaced intervals along the same which cause the two to be moved frontwardly by the push against the feeler on a detecting beat when a working supply of filling is present and which cause movement of the feeler relative to the feeler guide in a direction longitudinally of the shuttle by the forward push upon the feeler when the filling is substantially exhausted, a member bearing against the feeler and moved by the feeler when filling is 85 substantially exhausted to effect replenishment of filling.

4. In a feeler mechanism for looms, the combination of a feeler guide, a feeler having a portion extending alongside the feeler guide, cam connections at spaced intervals between the feeler guide and said portion, yielding means for holding the cam connections in engagement, and a single spring 90 acting upon the feeler guide for holding both the feeler guide and feeler in rearward position.

5. In a feeler mechanism for looms, the combination of a feeler guide mounted for movement toward and from the front of the loom and extending in the general direction in which it moves, a filling engaging feeler 100 extending substantially parallel to the feeler guide and mounted for movement toward and from the front of the loom and longitudinally of the shuttle, means for yieldingly forcing the feeler guide rearwardly, connections at spaced intervals between the feeler guide and feeler constructed and arranged to move the feeler away from the feeler guide in a direction longitudinally of the shuttle when the feeler is moved frontwardly by the forward push of a surface 110 within the shuttle and is not held from moving longitudinally of the shuttle by the filling.

6. In a feeler mechanism for looms, the combination of a feeler guide mounted for movement toward and from the front of the loom, a feeler having a portion extending alongside the feeler guide, connections at spaced intervals between the feeler guide and said feeler portion for causing both the feeler 125

and feeler guide to be moved frontwardly by the push upon the feeler when a working supply of filling is present in the shuttle on a detecting beat and for causing movement of the feeler in a direction longitudinally of the shuttle by the frontward push of a surface within the shuttle when the filling is substantially exhausted, and a spring for holding the connections in yielding engagement.

7. In a feeler mechanism for looms, the combination of a feeler guide mounted for movement toward and from the front of the loom, a feeler having a portion extending alongside the feeler guide, connections at spaced intervals between the feeler guide and said feeler portion for causing both the feeler

and feeler guide to be moved frontwardly by the push upon the feeler when a working supply of filling is present in the shuttle on a detecting beat and for causing movement of the feeler in a direction longitudinally of the shuttle by the frontward push of a surface within the shuttle when the filling is substantially exhausted, a lever having an end bearing against the feeler and moved by it when the feeler is moved longitudinally of the shuttle, and a spring acting through the lever and yieldingly holding the said connections in engagement.

In testimony whereof, I have signed my name to this specification.

ISAAC SNOW.
